J. A. AMOS

SIGNAL LANTERN

Filed March 17, 1924

INVENTOR
John A. Amos
BY E. E. Chapman
ATTORNEY

UNITED STATES PATENT OFFICE.

JOHN A. AMOS, OF ST. LOUIS, MISSOURI, ASSIGNOR TO OLIVER ELECTRIC AND MANUFACTURING COMPANY, OF ST. LOUIS, MISSOURI, A CORPORATION OF MISSOURI.

SIGNAL LANTERN.

Application filed March 17, 1924. Serial No. 699,879.

To all whom it may concern:

Be it known that I, JOHN A. AMOS, a citizen of the United States of America, residing at the city of St. Louis, State of Missouri, United States of America, have invented a certain new and useful Signal Lantern, of which the following is such a full, clear, and exact description as will enable any one skilled in the art to which it appertains to make and use the same, reference being had to the accompanying drawings, forming part of this specification.

My invention relates to an electric lantern, particularly intended for use by train men for signalling, which has the novel and advantageous characteristics hereinafter set forth.

In the accompanying drawings which illustrate an embodiment of my invention, Figure 1 is a side elevational view; Figure 2 is a view partly in elevation and partly in vertical section; Figure 3 is a bottom plan view; and Figure 4 is a plan view of the switch mechanism and certain associated parts.

The lantern comprises a casing 1, preferably in the form of a casting and provided with spaced integral feet 2, the ends of these feet being joined by the ring 3 integral therewith. In a suitable recess in the casing wall as shown is located a disk of insulating material 4, which forms a closure for the lower end of the casing and which supports the battery 5. An annular disk of copper or other suitable conductive material 6 is attached to the upper face of this disk by means of ears 7 extending through the disk 4 and bent over into engagement with the under surface thereof. A central contacting member 8 is also located on the upper surface of the disk within the conducting ring 6 and is electrically connected to the switch blade 9 by means of the screw 10, which forms the pivot for said blade. The disk 4 also carries lamp sockets 11, and the conducting ring 6 is provided with depressed portions as shown, which are adapted to be engaged by the central terminal of an electric lamp bulb 12 when the same is screwed into the socket. The positive and negative terminals of the battery 5 are in the form of resilient strips 13 and 14, which are held in contact with

the plates 6 and 8. In view of the central location of the terminal 14 and the annular shape of the contact plate 6, no attention to position of the battery terminals is required in placing the battery in the casing, since proper contacts will be made in any position.

The lantern is provided with a pivoted handle 15, which is frictionally held at any adjusted angle to the lantern casing by means of the fibre washers 27. The pivoted cover 16 of the casing is dome-shaped and is held closed by the spring latch 26. On the under surface of the cover is carried spring member 17 which bears upon the top of the battery and holds it against motion relative to the casing, and also constitutes means for holding the battery terminals in electrical contact with the contact members referred to when the lantern is swung to a position in which the weight of the battery would tend to separate these contacts. The shape of the cover also affords space for the carrying of spare lamp bulbs, which are held by the spring clip 18.

The switch mechanism is mounted on the under side of the insulating plate 4 and comprises a switch blade 9 actuated by handle 19 and pivoted on the screw shank 10, as previously described. The lantern is provided with two lamp sockets 11, from each of which conducting strips 20 extend for engagement with the switch arm. These members 20 are preferably provided with depressions 21 into which a struck-up portion of the switch blade enters in making contact, and serve to hold the switch lever in the circuit closed positions.

As a further means for holding the lever in "on" positions depressions 22 are made in the under surface of the insulating plate 4, which are engaged by the struck-up portion of the forward end of the lever in the "on" positions of the switch. While a single lamp is sufficient for signalling purposes, the provision of two lamps and arrangement of contacts so that moving the switch blade in either direction from its "off" position will close a lamp circuit, has the advantages that the operator need give no attention to which direction he pushes the switch arm, and that if one lamp filament should burn out while the lantern was being used in the giving of a particular signal, moving of the switch

arm in the opposite direction will light the other filament and the signal can be immediately repeated. This latter is a particularly important feature with respect to 5 safety and convenience as will be readily understood.

The switch mechanism and lamp sockets are covered by the housing 23, which housing, together with the disk 4, are held in 10 position by screws 24 entering the casing. This housing 23 also carries guard-wires 25, which protect the lamp bulbs from breakage when the lantern is set down on a surface of rock or cinders, it being understood 15 that the bottom of the lantern must be open in order that view of the light from a distance may not be obstructed during any signalling motions of the lantern. Since the lantern has a skeleton base it has the advantage 20 that the light can be seen by the engineer even when the lantern is put down on the ground or station platform.

Having fully described my invention.

what I claim as new and desire to secure by Letters Patent of the United States is:

25

In an electric signalling device, the combination of a casing having a bottom closure of insulating material, two lamp sockets mounted on said closure and opening downward, an annular contact plate mounted on 30 the upper side of said closure, a battery in the casing having one terminal engaging said contact plate, a second contact member on said closure adapted to be engaged by the other battery terminal, a switch member in 35 electrical connection with said last mentioned contact member and movable to place same in circuit with a terminal of either lamp socket, the annular contact plate being so located with respect to the sockets that a 40 terminal of a lamp inserted in either of said sockets will engage with said contact plate.

In testimony whereof, I have hereunto set my hand this the 14th day of March, 1924.

JOHN A. AMOS. [L. s.]
